FILLING CARRIER TRANSFERRING
MECHANISMHorace H. Burdett, Milford, Mass., assignor to
Draper Corporation, Hopedale, Mass., a cor-
poration of Maine

Application April 9, 1943, Serial No. 482,420

6 Claims. (Cl. 139—243)

The present invention relates to filling replenishing looms and, as illustrated herein, relates more particularly to means for controlling the operation of mechanism for transferring successive filling carriers to a shuttle during operation of the loom.

In automatic looms of the type referred to above, the filling carriers are transferred from the holder or hopper to the shuttle without interrupting the operation of the loom. The transfer operation is performed as the lay approaches front center and takes place in a very short period of time. Such rapid operation, which is performed suddenly and almost instantaneously, necessarily entails considerable strain and shock, particularly in stopping the transfer mechanism at the end of its transferring movement. It has not been practical to provide a solid stop to limit movement of the transfer mechanism because of the high speed of the parts. Stopping of the transfer mechanism has been effected by the use of a tension spring which operates also to return the transfer mechanism to its initial position and also operates to rotate the bobbin holding mechanism to present another bobbin or filling carrier into transfer position. A very heavy spring has been necessary in order to stop the mechanism at a predetermined desired point. Such a heavy spring, however, is objectionable since it causes undue wear on the parts.

One object of the present invention, accordingly, is to provide means for stopping the transfer mechanism by the use of which the above mentioned objections will be overcome. In accordance with this object, one feature of the invention comprises a transerrer movable for transferring successive filling carriers from a holder and resilient means arranged to resist movement of the transerrer only during the latter portion of its transferring movement and forming a stop to limit operating movement of the transerrer. As illustrated, the stop member comprises a block of resilient material, preferably rubber, which is adjustably secured in position on the transerrer. This construction is effective and stops the transerrer without undue shock and strain on the parts. The construction also permits a lighter tension spring to be used and, consequently, wear on the transerrer parts is substantially reduced.

With the above and other objects and features in view, the invention will now be described with particular reference to the accompanying

drawing which illustrates a preferred embodiment thereof and in which:

Fig. 1 is a view in side elevation, partly in section, showing the transfer mechanism in operated position;

Fig. 2 is a detail view on an enlarged scale of a portion of a transerrer having a resilient adjustable stop applied thereto; and

Fig. 3 is a sectional view taken along the line III—III of Fig. 2.

The loom frame 10 is of usual construction and is provided with a hopper stand 12 on which is mounted a rotatable hopper of which only the butt end disk 14 is shown. The disk 14 is provided with the usual bobbin seats 16 and a ratchet 18 is fixed to the disk 14 in the usual manner. The ratchet is rotated step-by-step to move successive filling carriers 20 into transferring position.

The transerrer 22 is of usual construction and is supported for rocking movement on a stud 24 fixed to the hopper stand 12. An arm 26 projects downwardly from the hub 28 of the transerrer 22 and is pivotally connected at its lower end to a latch finger 30, the end 32 of which is arranged, upon transfer or replenishment of filling, to be raised into the path of movement of a bunter 34 carried by the lay 36. A feed pawl 38 of usual construction is carried by the transerrer on a pin 40 and operates to rotate the butt end disk 14 when the transerrer 22 is returned to its initial or inoperative position under the influence of the usual torsion spring 42.

When a filling carrier 20 is in transferring position and substantial exhaustion of the filling on a carrier in the shuttle 43 has been indicated by suitable feeling mechanism, the bunter 34 will engage the latch finger 30 as the lay moves into its forward position. Thus, the depending arm 26 will be swung rapidly in a clockwise direction and causes the transerrer 22 to be swung rapidly downwardly to move a filling carrier 20 out of a seat 16 in the disk 14 and down into engagement with the empty or substantially empty filling carrier 20, and forcing said last mentioned filling carrier out of the shuttle. As the lay begins its rearward movement, the transerrer begins to move upwardly under the influence of the spring 42. The feed pawl 38 moves with the transerrer and rotates the disk 14 in a direction to move the next filling carrier 20 into transferring position.

The parts described above are of usual construction and operate at the high speeds usual in modern high speed looms. The transerring

operation takes place during a very short period of time and without stopping the loom. There is considerable lost motion between the various parts of the transferring mechanism and hence it is difficult to prevent overthrow of the transfer-
ferrer. Such overthrow is prevented to a sub-
stantial extent by the spring 42 which also acts to return the transfer-
rerrer to its initial position. However, when the parts become worn the action of the spring 42 is not sufficient to prevent over-
throw and, consequently, the worn parts must be replaced.

Downward movement of the transferrer 22 is limited in the present construction by a resilient member 44 which is secured to the transferrer 22 and engages the top surface of the front box plate 46 of the right hand shuttle box. The transferrer 22 is provided with a ledge or shelf 48 which is provided with a threaded opening 50. The resilient member 44 comprises a block 52 formed of rubber or other suitable resilient material which is bonded to the lower face of a disk 54 and which is provided with an upwardly extending threaded shank 56 threaded into the opening 50. The resilient member is locked in adjusted position on the transferrer by the washer 58 and lock nut 60.

The resilient stop member 44 acts not only to cushion the stopping of the transfferer 22 but also acts to aid in the return of the transfferer 22 to its initial position. The resilient stop member 44 is assembled on the transfferer 22 and is so adjusted that the block 52 is compressed against the top of the front box plate 46 to an extent sufficient to overcome the pressure of the transfferer and to stop the transfferer in the proper position. When the lay begins its rearward movement, the pressure on the transfferer is released and the expansion of the rubber stop member 44 initiates the feeding movement of the feed pawl 38. Consequently, the tension of the torsion spring 42 can be reduced which will reduce wear on the feed pawl and the teeth of the ratchet 18.

Having thus described my invention, what I claim as new and desire to secure by Letters Patent of the United States is:

1. In a filling replenishing loom, a holder for a series of filling carriers, a transfer movable in one direction to transfer successive filling carriers from the holder, a spring for moving the transfer in the other direction, a stop, and resilient means carried by the transfer and arranged to engage the stop as the transfer approaches the limit of its transferring movement.

2. In a filling replenishing loom, a holder for a series of filling carriers, a transfferer movable

to transfer successive filling carriers from the holder, a member adjustably secured to the transferrer, and a resilient member fixed to the adjustable member and arranged to resist movement of the transferrer during only the latter portion of its transferring movement.

3. In a filling replenishing loom, a holder for a series of filling carriers, a transerrer mounted for movement to transfer successive filling carriers from the holder, a shuttle box, and adjustable resilient means mounted on the transerrer and arranged to engage the shuttle box as the transerrer approaches the end of its transferring movement to limit the movement of the transerrer.

4. In a filling replenishing loom, a holder for a series of filling carriers, a transfferer mounted for movement to transfer successive filling carriers from said holder, a shuttle box, having a front box plate, adjustable means mounted on the transfferer, and a resilient pad fixed to said adjustable means and arranged to engage the front box plate of the shuttle box as the transfferer approaches the end of its transferring movement to limit the movement of the transfferer.

5. In a filling replenishing loom, a rotatable holder for a series of filling carriers, a reciprocating lay having a shuttle box on one end thereof of adjacent said holder, a fly shuttle received in said shuttle box, a transerrer mounted for movement to transfer successive filling carriers from said holder to said shuttle when the supply of filling on the filling carrier in the shuttle is substantially exhausted, adjustable means mounted on the transerrer, and a resilient member fixed to said adjustable member and arranged to engage said shuttle box as the transerrer approaches the end of its travel.

proaches the end of its transferring movement.

6. In a filling replenishing loom, a rotatable holder for a series of filling carriers, a reciprocating lay, a shuttle box on the end of said lay adjacent said rotatable holder, a shuttle arranged to be picked across said lay and into said shuttle box, a transfferer associated with said holder and mounted for movement to transfer successive filling carriers from said holder to said shuttle when the supply of filling on the filling carrier in the shuttle is substantially exhausted, a member adjustably secured to the transfferer, means for locking said member in adjusted position, and a resilient rubber cushion fixed to said member and arranged to engage the front wall of said shuttle box as the transfferer approaches the end of its transferring movement to limit the movement thereof.
